LIFT CONTROL SYSTEMS

William John Bailey, Bexley, England, assignor to J. & E. Hall Limited, London, England, a company of Great Britain

Application January 2, 1958, Serial No. 706,836

Claims priority, application Great Britain
January 14, 1957

16 Claims. (Cl. 187—29)

This invention relates to lift control systems and is concerned with lift control systems of the kind in which a plurality of cars is arranged for serving a number of floors, the system being capable of operating the cars in any one of a plurality of different modes, the different modes being appropriate to different traffic conditions.

According to a first aspect of the present invention there is provided a lift control system for a plurality of cars arranged to serve a number of floors, the system comprising means for operating the cars in any one of a plurality of different modes, said modes including a first mode of operation that is suitable for heavy traffic in one direction and a second mode of operation that is suitable for normal traffic conditions, means associated with each car for determining whether the car is loaded, and selection means for causing the cars to be operated in the first mode when a predetermined time relationship exists between the periods during which loaded cars are travelling in said one direction and for causing the cars to be operated in said second mode when no other mode is selected.

According to another aspect of the present invention there is provided a lift control system for a plurality of cars arranged to serve a number of floors, the system comprising means for operating the cars in any one of a plurality of different modes, said modes including a first mode of operation that is suitable for heavy up traffic, a second mode of operation that is suitable for heavy down traffic and a third mode of operation that is suitable when there is heavy traffic in neither direction, means for each car for determining whether the car is loaded, first means for each car for registering the loaded condition of the car when the latter is travelling upwardly, second means for each car for registering the loaded condition of the car when the latter is travelling downwardly, and selection means for causing the cars to be operated in the first mode when a first predetermined number of the first registering means have been operated for periods between adjacent ones of which there is not more than a first predetermined time interval during which none of the first registering means is operated, for causing the cars to be operated in the second mode when a second predetermined number of the second registering means have been operated for periods between adjacent ones of which there is not more than a second predetermined time interval during which none of the second registering means is operated, and for causing the cars to operate in the third mode when no other mode is selected.

According to a further aspect of the present invention there is provided a lift control system of the kind referred to, wherein mechanism is provided for selecting the mode in which the system will operate, the selection being made in accordance with the relative amounts of up and down traffic as assessed by the loading of the cars and the directions in which the cars are travelling.

For a better understanding of the invention and to show how the same may be carried into effect reference will be made to the accompanying drawings in which

2

Figure 1 is a circuit diagram of mechanism for selecting the mode of operation of a lift system and Figures 2 and 3 are key sheets for Figure 1 showing the relay coils and their associated contacts in spindle form.

5 To facilitate an understanding of the lift system the following apparatus is listed:

BL—balanced peak selector relay coil;

DA, DB and DC—down coils of the cars A, B and C respectively;

10 DLA, DLB and DLC—down load relay coils for the cars A, B and C respectively;

DPT—down peak hold relay coil;

DSR—down peak selector relay coil;

LSRA, LSRB, LSRC—load switch relay coils for the cars A, B and C respectively;

UA, UB and UC—up coils for the cars A, B and C;

ULA, ULB and ULC—up load relay coils for the cars A, B and C respectively;

20 UPT—up peak hold relay coil;

USR—up peak selector relay coil.

The lift system is a modified form of that disclosed in co-pending Patent application No. 641,184 in which a plurality of cars serve a number of floors or landings.

25 The cars are arranged upon completion of a trip ordinarily to return to a particular floor which is termed the despatching floor. If, however, the system is arranged to operate with a free car (as described in said co-pending application), as calls are cleared the last car to be working remains at the floor to which it is last called and constitutes a "free car." Movement of each car is initiated either by a car call which is made by a person in the car and who desires to travel to a certain floor, or by a landing call that is initiated by a passenger waiting at one floor and who desires to travel to another floor.

30 Landing calls are supervised by a despatch signal initiating system to determine whether a landing call can conveniently be attended to by a car already on a trip or whether a further car that is waiting at the despatching floor should be despatched to attend to the landing call. The despatch signal initiating system selects the order for despatch of the cars and is arranged to delay the despatch signal until the expiry of a predetermined despatch interval, the despatch interval for each car being initiated

35 when the despatch signal is given to the previously selected car. Thus the despatch interval is an interval during which a car cannot be despatched to respond to a landing call. The system is arranged for selecting either the upper terminal floor or the lower terminal floor (ignoring any basement) as the despatching floor.

40 When the lower terminal floor is selected as the despatching floor the system is said to be on "up" despatch and when the upper terminal floor is selected as the despatching floor the system is said to be on "down" despatch. Means are provided for varying the despatch interval, either to be a long interval or to be a short interval. In the aforementioned co-pending application a manual traffic selection switch is provided. This switch has three operative positions. The switch is adjusted to its first operative position

45 to deal with heavy down traffic, to its second operative position to deal with normal traffic conditions and to its third operative position to deal with heavy up traffic.

50 The first position is known as "down peak" and in this position the system is caused to operate with downward despatch and with the shorter despatch interval. In the third position which is known as "up peak" the system is caused to operate with upward despatch and the shorter despatch interval. In the second operative position which is the "normal position" for balanced traffic the system operates on upward despatch with a variable despatch interval, the despatch interval being arranged to be long or short according to the positions of the cars in the

hatchways, the directions of travel of the cars and whether the cars are under despatch. (A car is under despatch when it has received its despatch signal but has not yet departed from the despatching floor).

The circuitry shown in the drawing of the present case replaces the manual means described in said co-pending application for selecting the mode of operation of the lift system, by means for automatically selecting the mode of operation in accordance with the traffic conditions of the system. The present automatic system is arranged for selecting one of four modes of operation, viz. "normal," "up peak," "down peak" and "balanced peak." The "normal" mode of operation is identical with the normal mode of operation of the system of said co-pending application. When on "up peak" the lift system operates with upward despatch and with the shorter despatch interval, some of the cars being arranged for by-passing certain down landing calls. When on "down peak" the system operates with downward despatch and with the shorter despatch interval, some of the cars being arranged for by-passing certain up landing calls. When on "balanced peak," the lift system operates on upward despatch with the shorter despatch interval but there is no such by-passing of calls as with "up peak" and "down peak." Selection of the mode of operation of the system is effected by three coils, viz. an up peak selector relay coil USR, a down peak selector relay coil DSR and a balanced peak selector relay coil BL. When the coil USR is energised the lift system operates on "up peak." When the coil DSR is energised the system operates on "down peak," when the coil BL is energised the system operates on "balanced peak" and when none of these three coils is energized the system operates on the "normal" mode. In Figure 1 relay coils have been indicated by a circle with the coil reference in the circle. In Figures 2 and 3 relay coils have been indicated by the conventional symbol.

Referring now to the circuit diagram in greater detail, a movable arm MA of a manual selector switch MSS is capable of assuming five operative positions and in these positions respectively connects contacts A to E to a positive supply line ML, there being a negative return line EL. The contact A is connected to a line L1 and when the manual selector switch is positioned to connect the line ML to the line L1 the lift system operates with automatic selection. The automatic selection mechanism will be described for use with a lift system having three cars, A, B and C (not shown) but it is to be understood that the mechanism can with slight modification be applied to system having any number of cars greater than one. Each car has therein a load switch (not shown) that is closed when the car is loaded to a predetermined extent. Each load switch is arranged when closed for energising an associated load switch relay coil (not shown) and each such coil when energized closes two associated pairs of contacts. The contacts for the car A are LSRA1 and LSRA2, for car B LSRB1 and LSRB2 and for car C LSRC1 and LSRC2. Two main control coils (not shown) are associated with the driving motor (not shown) of each car of the lift system. One of these two coils is an up coil which is energized to cause the motor to drive its car in the upward direction and the other coil is a down coil that is energised to cause the motor to drive its car downwardly. The up coils of the cars A, B and C each control two pairs of contacts and these are respectively UA1 and UA2, UB1 and UB2, and UC1 and UC2. Similarly, the down coils (not shown) of the cars A, B and C respectively control contacts DA1 and DA2, DB1 and DB2, and DC1 and DC2.

One contact of the pair of contacts LSRA1 is connected to the line L1 and the other contact is connected to a junction point JP1. One contact of the pair LSRB1 is connected to the line L1 and the other is connected to a junction point JP2. One contact of the pair LSRC1 is connected to the line L1 and the other contact is connected to a junction point JP3. The junction points

JP1, JP2 and JP3 are respectively connected through contacts UA1, UB1 and UC1 to a terminal 5 joined to the control grid of a valve V1 of a timer TX. The junction points JP1, JP2 and JP3 are also respectively connected through contacts DA1, DB1 and DC1 to a terminal 5 joined to the control grid of a valve V2 of a timer TY. The cathode of the valves V1 and V2 are each connected through an associated terminal 3 to the negative line EL. The anode of the valve V1 is connected through a terminal 4 and an up peak hold relay coil UPT to the line L1. The anode of the valve V2 is connected through an associated terminal 4 and a down peak hold relay coil DPT to the line L1.

The cathodes of the valves V1 and V2 are heated by the secondary winding of a transformer T the primary of which is connected across an A. C. supply.

Assuming that the line L1 is connected by the switch MSS to the line ML so that a positive potential is applied to the line L1, the valves V1 and V2 immediately conduct whenever the positive potential of line L1 is applied to their control grids. Following interruption of the circuit applying positive potential to the control grid of either of the valves, the associated valve ceases conducting approximately two minutes after such interruption.

One contact of the pair of contacts LSRA2 is connected to the line L1 and the other contact of this pair is connected to a junction point JP4. The contacts LSRB2 are connected between the line L1 and a junction point JP5 and the contacts LSRC2 are connected between the line L1 and a junction point JP6. The point JP4 is connected through the contacts UA2 and an up load relay coil ULA for the car A to the line EL. Point JP5 is connected through the contacts UB2 and an up load relay coil ULB for the car B to the line EL and the point JP6 is connected through the contacts UC2 and an up load relay coil ULC for the car C to the line EL. The point JP4 is also connected through the contacts DA2 and a down load relay coil DLA for the car A to the line EL, the point JP5 is connected through the contacts DB2 and a down load relay coil DLB for the car B to the line EL, and the point JP6 is connected through the contacts DC2 and a down load relay coil DLC for the car C to the line EL. The coil UPT controls contacts UPT1, the coil DPT controls contacts DPT1, the coil ULA controls contacts ULA1 to ULA4, the coil DLA controls contacts DLA1 to DLA4, the coil ULB controls contacts ULB1 to ULB4, the coil DLB controls contacts DLB1 to DLB4, the coil ULC controls contacts ULC1 to ULC4 and the coil DLC controls contacts DLC1 to DLC4. One contact of the pair of contacts UPT1 is connected to the line L1 and the other contact is connected to a junction point JP7. One contact of the pair DPT1 is connected to the line L1 and the other is connected to a junction point JP8. The positive sides of the coils ULA, ULB, ULC are respectively connected through contacts ULA1, ULB1 and ULC1 to the junction point JP7 and the positive sides of the coils DLA, DLB and DLC are respectively connected via the contacts DLA1, DLB1 and DLC1 to the junction point JP8.

The coil USR controls contacts USR1, USR2 and others (not shown), the coil DSR controls contacts DSR1, DSR2 and others (not shown) and the coil BL controls contacts BL1 to BL4 and others (not shown). The contacts ULA2, ULB2 and ULC2 are connected together in series between the line L1 and a junction point JP9, this point being connected through the contacts BL1 and DSR1 and the coil USR to the line EL. The contacts DLA2, DLB2 and DLC2 are connected together in series between the line L1 and a junction point JP10 which is connected to the line EL through the contacts BL2 and USR1 and the coil DSR.

One side of the coil BL is connected to the negative line EL and the other side of the coil is connected to a

junction point JP11. The point JP11 is connected to a line L2 through parallel connected contacts BL3 and DSR2. A line L3 is connected to the point JP11 through parallel connected contacts USR2 and BL4. The line L2 is connected to the line L1 through three parallel paths, the first of which consists of series-connected contacts ULA3 and ULB3, the second consisting of series-connected contacts ULA4 and ULC3 and the third consisting of series-connected contacts ULB4 and ULC4. The line L3 is connected to the line L1 through three parallel paths, the first of which consists of series-connected contacts DLA3 and DLB3, the second consisting of series-connected contacts DLA4 and DLC3 and the third consisting of series-connected contacts DLB4 and DLC4.

The contacts C and D of the manual switch MSS are respectively connected to the junction points JP9 and JP10. The contact E is connected to an earth return line through a relay coil which is energised when it is desired to put the lift system of said copending application on night service.

A movable arm MA1 of a clock selector switch CSS is connected to the line L1. The arm MA1 is clock driven to rotate once every twenty-four hours. The arm MA1 successively encounters segments 9, 12, 15, 18. The arm is in contact with each of these segments for a predetermined period, the segment 9 at a period around 9 a. m., the segment 12 at a period about noon, the segment 15 at a period about 3 p. m. and the segment 18 at a period about 6 p. m. The segments 9 and 15 are connected to the junction point JP9 and the segments 12 and 18 to the junction point JP10.

With the arm MA of the switch MSS in the position where the arm touches the contact A, the mechanism is set for automatic operation. Let it be assumed that all the cars are standing idle at the lower terminal floor. The mode of operation set by the mechanism is "normal" since the coils USR, DSR and BL are all de-energised. When calls for service are registered from the landings or by passengers in the cars, the cars answer these calls in the manner described in said co-pending application. So long as the loads in the cars do not exceed the pre-set value at which the load switches close, the lift system remains in the "normal" mode of operation (ignoring for the moment the function of the clock selector switch CSS).

If the load in, say, car A exceeds the pre-set value at some time during, say, the upward travel of this car, the load switch for car A will close and hence contacts LSRA1 and LSRA2 close. Contacts UA1 and UA2 are already closed as the car is travelling upwardly. Hence the valve V1 conducts and the coil UPT is energised and the contacts UPT1 are closed. Closure of the contacts LSRA2 and UA2 causes energisation of the up load coil ULA whereby contacts ULA1 to ULA4 close. Contacts UPT1 and ULA1 form a holding circuit for the coil ULA and this coil is maintained energised until the contacts UPT1 open, i. e. when the coil UPT becomes de-energised. The coil UPT becomes de-energised approximately two minutes after removal of the positive potential from the control grid of the valve V1. Thus provided car A is the only one upon which the load switch has operated, the coil ULA becomes de-energised approximately two minutes after car A reverses or after the load switch opens whichever is the earlier. Similarly, if the load in car A exceeds the preset value at some time during downward travel of the car A, the coil DLA is energised and holds for the pre-set time after opening of the contacts LSRA1 or DA1. For cars B and C, the coils ULB, DLB, ULC and DLC operate similarly to the coils ULA and DLA.

When car A is travelling upwardly in the loaded condition the contacts LSRA1 and UA1 are closed as are the contacts LSRA2 and UA2 so that the coils UPT and ULA are energised. If car B is in a condition where it is travelling upwardly with its load switch closed at a

time less than two minutes after reversal of the car A or opening of the load switch in car A, the coil ULB will of course have become energised and in addition the coil ULA will be maintained energised, since the coil UPT remains energised following closure of the contacts LSRA1 and UB1, whereby the holding circuit for the coil ULA is maintained closed. If now car C travels upwardly with its load switch closed at a time less than two minutes after the last of cars A and B to reverse has done so or after the last of cars A and B to be unloaded has become so or after one of them has reversed and the other has become unloaded, the coil ULC will be energised and the coils ULA and ULB will be maintained energised. When all three of coils ULA, ULB and ULC are energised, the contacts ULA2, ULB2 and ULC2 in series with the up peak selector relay USR are closed and as the contacts BL1 and DSR1 are at this time closed the coil USR is energised and the lift system operates on "up peak." In practice, of course, de-energisation of the coil UPT occurs as a result of opening of the load switches rather than reversal of the cars since the cars ordinarily become unloaded before they reverse.

The coils DLA, DLB and DLC control the down peak selector relay coil DSR in a similar way to the control exercised over the coil USR by the coils ULA, ULB and ULC. Thus it can be said that when cars A, B and C have all become loaded beyond a pre-set value for the same direction of travel and the interval between the periods of such loadings has not exceeded the time (approximately two minutes) set by timer TX or TY the coil USR is energised in the case of upward travel and the coil DSR is energised in the case of downward travel. The coil USR remains energised for the pre-set time, set by timer TX, after all of the upward travelling cars A, B and C have reduced their loads below the pre-set value. Similarly the coil DSR remains energised for the time set by the timer TY after all the downward travelling cars A, B and C have reduced their loads below the pre-set value.

With the circuit as shown, the relay coils USR and DSR cannot respond until all three cars have been loaded beyond the pre-set value, but it is to be understood that these relay coils can be arranged so that they respond to loading of any number of cars of the group as desired to suit the requirements of a particular installation.

The coils USR and DSR when energised respectively select "up peak" and "down peak" modes of operation of the lift system. It will be realised that once the selection has been made it is held for a pre-set time (about two minutes) after the subsidence of the peak and this time lag can, of course, be adjusted as desired by alteration of the time circuits of the valves V1 and V2. The time lag prevents selection changes taking place at two frequent intervals and thus short gaps between peak traffic conditions for the same direction do not cause discontinuance of peak selection.

Assume now that the condition of traffic is for "up peak" so that the relay coil USR is energised. If any two cars become loaded beyond the pre-set value in the downward direction, one of the three parallel paths between the lines L3 and L1 will be completed and as the contacts USR are closed, the coil BL will become energised. Energisation of the coil BL closes the contacts BL4 and opens the contacts BL1. Opening of the contacts BL1 causes the coil USR to be de-energised and closure of the contacts BL4 maintains the coil BL in the energised condition in spite of the opening of the contacts USR2. The lift system therefore assumes its "balanced peak" mode of operation. Similarly, when "down peak" traffic conditions exist so that the coil DSR is energised, loading of any two cars beyond the pre-set value whilst they are travelling upwardly causes the coil BL to become energised whereby the contacts BL2 open and BL3 close, the coil DSR becoming de-energised and the coil

BL being maintained energised by closure of the contacts BL3.

If first the up peak or the down peak traffic condition subsides, the mode of operation reverts to "normal" because all of the relay coils USR, DSR and BL are de-energised. If the balanced peak traffic condition first subsides, the mode of operation reverts to the prevailing up or down peak because the coil BL becomes de-energised.

The following table shows typical traffic conditions and the point at which automatic selection of the mode of operation takes place:

Sequence	Car becoming loaded to the preset load	Direction of travel of loaded car	Selected Mode of operation
1	A	Down	Normal balanced.
2	B	Down	" "
3	C	Down	Down peak.
1	A	Up	Normal balanced.
2	E	Up	Normal balanced.
3	C	Up	Up peak.
1	A	Down	Normal balanced.
2	B	Down	" "
3	C	Up	" "
4	A	Up	Peak balanced.
5	B	Up	Normal balanced.
1	A	Down	" "
2	B	Down	Down peak.
3	C	Down	" "
4	A	Up	Peak balanced.
5	B	Up	" "
6	C	Up	" "

With the manual selector switch MSS in the position where the arm MA encounters the contact A, the clock timing mechanism is operative. Whenever the arm MA1 encounters one of the segments 9, 12, 15, 18 a circuit is completed either through the up peak selector relay coil USR or the down peak selector relay coil DSR (provided the coil BL is not energised). If automatic selection of a peak has taken place immediately prior to completion of a circuit through the clock selector switch CSS, that peak condition remains set and is unaffected by the clock mechanism. When the clock time for a particular peak expires and the peak traffic still persists, the peak selection is held by the automatic selection until the peak subsides.

When the manual selector switch MSS is moved so that the arm MA encounters the contact B, both automatic and clock selection are inoperative and the mode of operation remains "normal" irrespective of changes in the traffic conditions. When the arm MA is moved to encounter the contact C or D, "up peak" and "down peak" respectively modes of operation are set and automatic selection and clock selection are inoperative. With the arm MA encountering the contact E, all selection mechanism is inoperative.

I claim:

1. A lift control system for a plurality of cars arranged to serve a number of floors, the system comprising means for operating the cars in any one of a plurality of different modes, said modes including a first mode of operation that is suitable for heavy traffic in one direction and a second mode of operation that is suitable for normal traffic conditions, means associated with each car for determining whether the car is loaded, and selection means for causing the cars to be operated in the first mode when a predetermined time relationship exists between the periods during which loaded cars are travelling in said one direction and for causing the cars to be operated in said second mode when no other mode is selected.

2. A lift control system for a plurality of cars arranged to serve a number of floors, the system comprising means for operating the cars in any one of a plurality of different modes, said modes including a first mode of operation that is suitable for heavy traffic in one direction and a sec-

ond mode of operation that is suitable for normal traffic conditions, means associated with each car for determining whether the car is loaded, and selection means for causing the cars to be operated in the first mode when a predetermined number of the cars travelling in said one direction have been loaded with not more than a predetermined time interval between adjacent periods for which these cars are both loaded and are travelling in said one direction, and for causing the cars to be operated in said second mode when no other mode is selected.

3. A lift control system for a plurality of cars arranged to serve a number of floors, the system comprising means for operating the cars in any one of a plurality of different modes, said modes including a first mode of operation

15 that is suitable for heavy up traffic, a second mode of operation that is suitable for heavy down traffic and a third mode that is suitable for normal traffic conditions, means associated with each car for determining whether the car is loaded, and selection means for causing the cars to be operated in said first mode when a predetermined time re-

20 lationship exists between the periods during which loaded cars are travelling upwardly, for causing the cars to be operated in the second mode when a second predetermined time relationship exists between the periods during which loaded cars are travelling downwardly, and for causing the cars to be operated in the third mode when no other mode is selected.

4. A lift control system for a plurality of cars arranged to serve a number of floors, the system comprising

30 means for operating the cars in any one of a plurality of different modes, said modes including a first mode of operation that is suitable for heavy up traffic, a second mode of operation that is suitable for heavy down traffic and a third mode that is suitable for normal traffic con-

35 ditions, means associated with each car for determining whether the car is loaded, and selection means for caus- ing the cars to be operated in the first mode when a predetermined number of the cars travelling upwardly have been loaded with not more than a predetermined time

40 interval between adjacent periods for which these cars are both loaded and travelling upwardly, for caus- ing the cars to be operated in the second mode when a predetermined number of the cars travelling downwardly have been loaded with not more than a predetermined time

45 interval between adjacent periods for which these cars are both loaded and travelling downwardly, and for causing the cars to be operated in the third mode when no other mode is selected.

5. A lift control system for a plurality of cars arranged

50 to serve a number of floors, the system comprising means for operating the cars in any one of a plurality of different modes, said modes including a first mode of operation that is suitable for heavy up traffic, a second mode of operation that is suitable for heavy down traffic and a

55 third mode of operation that is suitable when there is heavy traffic in neither direction, means for each car for determining whether the car is loaded, first means for each car for registering the loaded condition of the car when the latter is travelling upwardly, second means for

60 each car for registering the loaded condition of the car when the latter is travelling downwardly, and selection means for causing the cars to be operated in the first mode when a first predetermined number of the first registering means have been operated for periods be-

65 tween adjacent ones of which there is not more than a first predetermined time interval during which none of the first registering means is operated, for causing the cars to be operated in the second mode when a second predetermined number of the second registering means

70 have been operated for periods between adjacent ones of which there is not more than a second predetermined time interval during which none of the second registering means is operated, and for causing the cars to be operated in the third mode when no other mode is

75 selected.

6. A control system as claimed in claim 5, wherein the first and second intervals are of equal duration of time.

7. A control system as claimed in claim 5, wherein the first and second predetermined numbers of cars are each equal to the number of cars in the system.

8. A control system for a plurality of cars arranged to serve a number of floors, the system comprising means for operating the cars in any one of a plurality of different modes, said modes including a first mode of operation that is suitable for heavy up traffic, a second mode of operation that is suitable for heavy down traffic and a third mode of operation that is suitable when there is heavy traffic in neither direction, means for each car for determining whether the car is loaded, first means for each car for registering the loaded condition of the car when the latter is travelling upwardly, second means for each car for registering the loaded condition of the car when the latter is travelling downwardly, and selection means for causing the cars to be operated in the first mode when a first predetermined number of the first registering means have been operated for periods between adjacent ones of which there is not more than a first predetermined time interval during which none of the first registering means is operated, for causing the cars to be operated in the second mode when a second predetermined number of the second registering means have been operated for periods between adjacent ones of which there is not more than a second predetermined time interval during which none of the second registering means is operated, and for causing the cars to be operated in the third mode when no other mode is selected, said selection means including means for causing a mode other than the first mode to be selected when whilst the first mode is in operation said first predetermined interval occurs and means for causing a mode other than the second mode to be selected when whilst the second mode is in operation said second predetermined interval occurs.

9. A control system for a plurality of cars arranged to serve a number of floors, the system comprising means for operating the cars in any one of a plurality of different modes, said modes including a first mode of operation that is suitable for heavy up traffic, a second mode of operation that is suitable for heavy down traffic and a third mode of operation that is suitable when there is heavy traffic in neither direction, means for each car for determining whether the car is loaded, first means for each car for registering the loaded condition of the car when the latter is travelling upwardly, second means for each car for registering the loaded condition of the car when the latter is travelling downwardly, selection means for causing the cars to be operated in the first mode when a first predetermined number of the first registering means have been operated for periods between adjacent ones of which there is not more than a first predetermined time interval during which none of the first registering means is operated, for causing the cars to be operated in the second mode when a second predetermined number of the second registering means have been operated for periods between adjacent ones of which there is not more than a second predetermined time interval during which none of the second registering means is operated, and for causing the cars to be operated in the third mode when no other mode is selected, and means for preventing a change of selection from the first mode to the second mode until after said first predetermined interval has occurred and for preventing a change of selection from the second mode to the first mode until after said second predetermined interval has occurred.

10. A lift control system for a plurality of cars arranged to serve a number of floors, the system comprising means for operating the cars in any one of a plurality of different modes, said modes including a first mode of operation that is suitable for heavy up traffic, a second

mode of operation that is suitable for heavy down traffic and a third mode of operation that is suitable when there is heavy traffic in neither direction, a load switch for each car for determining when the associated car is loaded to a predetermined extent, first means for each car for registering the loaded condition of the car when the latter is travelling upwardly, second means for each car for registering the loaded condition of the car when the latter is travelling downwardly, and selection means for causing the cars to be operated in the first mode when a first predetermined number of the first registering means have been operated for periods between adjacent ones of which there is not more than a first predetermined time interval during which none of the first registering means is operated, for causing the cars to be operated in the second mode when a second predetermined number of the second registering means have been operated for periods between adjacent ones of which there is not more than a second predetermined time interval during which none of the second registering means is operated, and for causing the cars to be operated in the third mode when no other mode is selected.

11. A lift control system for a plurality of cars arranged to serve a number of floors, the system comprising means for operating the cars in any one of a plurality of different modes, said modes including a first mode of operation that is suitable for heavy up traffic, a second mode of operation that is suitable for heavy down traffic, a third mode of operation that is suitable when there is heavy traffic in neither direction and a fourth mode that is suitable for simultaneous heavy up and heavy down traffic, means for each car for determining whether the car is loaded, first means for each car for registering the loaded condition of the car when the latter is travelling upwardly, second means for each car for registering the loaded condition of the car when the latter is travelling downwardly, and selection means for causing the cars to be operated in the first mode when a first predetermined number of the first registering means have been operated for the period between adjacent ones of which there is not more than a first predetermined time interval during which none of the first registering means is operated, for causing the cars to be operated in the second mode when a second predetermined number of the second registering means have been operated for periods between adjacent ones of which there is not more than a second predetermined time interval during which none of the second registering means is operated, for causing the system to change from the first mode to the fourth mode when a third predetermined number of the second registering means have been operated for periods between adjacent ones of which there is not more than a third predetermined time interval during which none of the second registering means is operated, for causing the system to change from the second mode to the fourth mode when a fourth predetermined number of the first registering means have been operated for periods between adjacent ones of which there is not more than a fourth predetermined time interval during which none of the first registering means is operated, and for causing the cars to be operated in the third mode when no other mode is selected.

12. A control system as claimed in claim 11, wherein the second and third intervals are equal and the first and fourth intervals are equal.

13. A control system as claimed in claim 11, wherein the third predetermined number is less than the second predetermined number and the fourth predetermined number is less than the first predetermined number.

14. A control system as claimed in claim 11, wherein the selection means includes means for causing the system to change from the fourth mode to another mode when any one of said intervals occurs.

15. A lift control system for a plurality of cars arranged to serve a number of floors, the system comprising

11

means for operating the cars in any one of a plurality of different modes of operation suitable for different traffic conditions, traffic determining means for assessing traffic in accordance with the loading of the cars and the directions in which the cars are travelling, and selection mechanism for selecting the mode in which the system operates in accordance with the traffic as assessed by said traffic determining means.

16. A lift control system for a plurality of cars arranged to serve a number of floors, the system comprising means for operating the cars in any one of a plurality of different modes of operation suitable for different traffic conditions, traffic determining means for assessing traffic in accordance with the loading of the cars and the

10

12

directions in which the cars are travelling, selection mechanism for selecting the mode in which the system operates in accordance with the traffic as assessed by said traffic determining means, and a manual selector switch for setting the system to operate in a particular one of said modes irrespective of the loading of the cars and their directions of travel.
